UNITED STATES PATENT OFFICE.

SOLOMON A. WOODS, OF BOSTON, MASSACHUSETTS.

PLANING-MACHINE.

SPECIFICATION forming part of Letters Patent No. 364,743, dated June 14, 1887.

Application filed February 2, 1887. Serial No. 226,214. (No model.)

To all whom it may concern:

Be it known that I, SOLOMON A. WOODS, of Boston, in the county of Suffolk and State of Massachusetts, have invented a certain new and useful Improvement in Planing-Machines, 5 of which the following is a specification.

My improvement relates to machines for planing and preparing lumber; and it consists in certain new and useful constructions and 10 combinations of the parts of the same, substantially as hereinafter described and claimed.

In the drawings, Figure 1 is a top plan view of 15 a planing-machine constructed with my improvements. Fig. 2 is a longitudinal vertical section of the same. Fig. 3 is a side elevation of the same. Fig. 4 is a top plan view of the same, similar to Fig. 1 in general construction, but with a different arrangement of the side or matching cutters in having both adjustable toward the 20 central guide and the guide made tapering. Fig. 5 is an enlarged view of a portion of Fig. 4, showing the details of its mechanism and having only a single central cutter applied on one side of the central guide. Fig. 6 is a side 25 elevation of Fig. 5 with the frame-work of the upper feed-rolls and gears of the upper and lower feed-rolls removed for the sake of clearness of illustration. Fig. 7 is a transverse view of Fig. 5 on the dotted line *z z*. Fig. 8 is a similar transverse view of the like parts 30 with the matching-cutters arranged as shown in Fig. 1. Fig. 9 is a top plan view of the planing-machine shown in Figs. 1 and 4, with a modified arrangement of the matching-cutters and central guide. Fig. 10 is a transverse 35 section of the same at the corresponding place and showing the corresponding parts to Fig. 7. Figs. 11 and 12 show a longitudinal section and an end view of details of Figs. 1 and 4c 4c enlarged. Fig. 13 is a detail top plan view 45 of one of the cutters shown in Fig. 8 with a portion of the board being worked and the central and outer guides. Fig. 14 is a transverse section of Fig. 13 on the dotted line *yy*. Figs. 15 and 16 are detail side and end views 50 of parts of the machine, showing one method of securing the central guide-strip in place. Fig. 17 and 18 are similar views of the same details, showing another way of securing said guide-strip. Fig. 19 is a transverse vertical section across Fig. 4, in front of the first pair 55 of feed-rolls, showing the upper rolls in sec-

tion, with their mode of attachment to the central hanger. Fig. 20 is a detail view of part of Fig. 19.

The planing-machine in question is what is commonly known as a "duplex" planer—that is, one in which two boards can be dressed and matched at the same time—but it is so constructed as to be altered into a single planer, 60 capable of receiving, dressing, and matching one wide board by removing the duplex attachments out of the way. My improvements are designed to facilitate this transformation from a duplex to a single machine, or vice 65 versa, and to increase the breadth of the parts of the duplex bed in proportion to the breadth of the whole bed, and to simplify the adjustment of the several parts for performing work on two boards at once.

A is the frame of the machine. The top planing-cylinder, *a*, bottom planing-cylinder, *a'*, feed-rolls *a² a³ a⁴*, and their driving-countershafts, gears, bed-plates, and other similar parts connected therewith are of the well-known construction and do not require further description, except that the top rolls of the first two pairs of rolls are divided in the middle in one modification, and each half of the top roll, 20 and 21, is hung upon a separate shaft, which is journaled at its inner end in a box, *b'*, in hanger *b*, depending from the cross-girt 22, as shown in Figs. 4, 9, 19, and 20. The box *b'* is pressed down in the hanger by a spiral spring, *b²*. This modification of 75 the construction of the feed-rolls, taken by itself, is, however, also well known, and I only claim the same in connection with the tonguing cutters and other features, as hereinafter set forth in the claims.

In order to provide for the tonguing and matching of the lumber as it is run through the machine, when it is used as a single machine, two upright cutter-heads, *c c'*, are mounted in the frame of the machine in the 80 customary manner and provided with tonguing and grooving cutters. The cutter-head *c* is connected to the side guides, *c² c³*, and the whole of them are adjusted across the machine by the shaft *c⁴* in the manner shown and described in the patent granted to S. A. Woods, October 19, 1886, No. 351,303. The shaft *c⁴* is operated by a crank upon the end of it upon 85 one side of the machine, and in order to fa-

elilitate the operation of the different sections of it, as hereinafter described, one of the transverse screws operating the cutter-head c is extended through the frame of the machine to 5 the opposite side, and another crank, c^6 , is attached to it. Another of the screws adjusting the guide c^2 near the feed-in end of the machine is also extended through the frame in like manner and has the hand-wheel 40 attached to it. This hand-wheel thus enables the operator to revolve the section of the shaft which controls the outer guide strip, c^2 , while the crank c^6 controls the cutter-head c , and the crank on the end of the shaft c^4 revolves that 10 part of it which controls the guide-strip c^2 , and these several attachments can thus be separately adjusted when the sections of the shaft c^4 are uncoupled from each other, as hereinafter described. The guides c^2 and cutter-head c are adjusted with relation to the central guide, D, introduced in the machine to 15 render its action duplex; in the manner hereinafter described; but in order to adjust them differentially with relation to each other, as described in said Letters Patent, I have devised an improved form of couplings, c^6 c^7 , (shown in detail in Figs. 11 and 12,) in lieu of loosening the bevel-gears to accomplish such differential adjustment. The coupling c^6 unites 20 the portion of the shaft c^4 (having the crank upon its end) which carries the bevel-gears adjusting the guide c^2 to the next section of the said shaft c^4 , which carries the bevel-gear operating to adjust the cutter-head c . The coupling c^7 in turn connects this latter section of 25 the shaft c^4 to the next section of it carrying the three bevel-gears, which operate to adjust the guide c^2 transversely of the table. This coupling consists of a sleeve, c^8 , of metal, into 30 which is securely pinned one section of the divided shaft c^4 . The other section of said divided shaft is introduced into the bore of the sleeve from its opposite end, having a groove, c^9 , circumferentially around it. A set screw, 35 c^{10} , is tapped through the wall of the sleeve c^8 in such a position that the groove c^9 of the section of the shaft containing it may be brought opposite the point of the set-screw, as shown in Fig. 11. When the set-screw is tightened 40 up on this section of the shaft c^4 , it unites the sections together and causes them to turn the bevel-gears upon them equally and move the guides c^2 and the cutter-head c equally. When it is desired to move the guide c^2 without 45 moving the cutter-head c , or when it is desired to move the guide c^2 and cutter-head c without moving the guide c^2 , the set-screw c^{10} of the proper coupling is loosened slightly, thereby allowing the coupling to revolve upon 50 the section of the shaft c^4 against which the set-screw bears, and this section will therefore remain stationary. The function of the groove c^9 is to hold the section of the shaft in 55 which it is made in the same longitudinal position within the coupling, whether it be stationary or movable with the coupling. The advantage of this method of coupling the sec-

tions of the shaft c^4 together is that it insures perfect adjustment and rotation of all the working parts, whether coupled or uncoupled, and 70 requires a less amount of time and labor to perform the necessary adjustments.

In order to make the machine a duplex planer I attach to its bed a longitudinal central guide, D, as shown. This guide has its 75 edge or edges which direct the board through the machine inclined to the axis of the rolls, either by being made tapering or set at the proper angle. This guide is either gained into the bed of the machine, as shown in Figs. 15 and 16, or it is attached to the bed by pins 80 projecting downward into holes in the bed, as shown in Figs. 17 and 18, or both of these methods may be employed to secure it in position. In case these holding pins come over 85 the grooves in which the side guide moves, as in Fig. 9, their holes in the bed are made in the bottoms of these grooves. These transverse grooves across the bed serve as guideways for the side guides, and are constructed 90 in the usual manner. This longitudinal central guide-strip may be made in one piece extending the whole length of the machine, or it may be made in two sections, according as 95 convenience may require it to be adapted to machines of slightly-different constructions of bed and other similar parts.

In order to give the greatest possible space for planing and tonguing and grooving two 100 boards simultaneously, one on each side of the central guide, D, this guide must be made as narrow transversely of the machine as possible, and I have therefore arranged to form the tongues on the edges of the boards, respectively, which come next to this central 105 guide, and to use the vertical cutter-heads c^2 for forming the grooves in the opposite edges of these boards as they pass through the machine, and I have further arranged to form these tongues on each side of the guide D by 110 a pair of cutter-heads mounted on horizontal shafts arranged transversely of the machine, each cutter-head of the pair being adjusted to receive and carry two knives or cutters, one of which cuts the board on each side of the 115 central guide, D, above and below the edge of the board, and forms one-half of the tongue, as shown in Figs. 1 and 8. These cutter-heads are placed in advance of the planing-cylinders a a' , because their cutters, revolving so as to 120 cut the board from the planed toward the unplaned surface in forming the tongue, create a roughness along the edge of the path or groove cut by them toward the center of the board, especially when the last portion of their 125 cutting as they pass through the wood is considerably the widest, as shown in Fig. 4, and this roughness is removed by the subsequent action of the planing-cylinder a in planing the upper surface of the board and by the 130 action of the cylinder a' in planing the lower surface of the board. This gives a more perfect finish to this edge of the board where it joins the tongue than if the tongue be formed

by cutters attached to cylinder *a*. The cause of the last portion of the cutting of the matching-cutters being the widest is that they cut from the planed toward the unplaned portion 5 of the stock, and thus when the cutter projects vertically downward it cuts an even depth from point to heel off the edge of the board, but as it progresses toward the point where it leaves the board the inclined position of the latter to the axis of the cutter 10 causes its outer end to cut deepest.

e e' are the horizontal shafts, having pulleys *p* and *p'* upon their outer ends, by which they are driven from the pulleys *p²* and *p³*, attached to countershafts near the end of the machine. The shaft *e* is mounted in a box or boxes, *b*, attached to the plate *b'*. This plate slides horizontally to and fro in guideways upon a plate, *b²*, and the plate *b²* slides up and down 15 on guideways *b³ b³*, which are upright bars attached together in the form of a bracket, *b⁴*, and to the frame of the machine. The plates *b'* and *b²* and guideways are attached together by the usual undercut or dovetail construction of slides, which are well understood and 20 shown in Fig. 5. This upper shaft, *e*, with these attached parts, is above the bed of the machine over which the lumber traverses. The plate *b'* has an ear, *n*, attached to it, and the plate *b²* has another ear, *n²*, attached to it, and a screw, *n³*, having a hand-wheel on its outer end, is journaled in the ear *n²* and fitted to a threaded hole in the ear *n*. By this means the plate *b'* can be moved horizontally on the 25 plate *b²* to adjust the cutters of the cutter-head to their proper positions with relation to the guide *D*. On the inner end of the shaft *e* is the cutter-head *e²*, which is made long enough to have the cutters *c¹³* and *c¹⁴* attached thereto by bolts *c¹² c¹²*, which are tapped into the cutter-head, the body of the bolts passing through slots in the cutters, as shown. The lower shaft, *e'*, is provided on its inner end with a similar cutter-head provided with similar cutters, *c¹³ c¹⁴*, secured to it in like manner. The bracket *b⁴* is attached to the cross-girt *d* (which is bolted to the frame of the machine) by guideways on the girt, on which the bracket *b⁴* is fitted to slide transversely of the machine, and an ear, *d'*, is attached to the cross-girt *d*, and has journaled in it a screw, *n⁴*, having a hand-wheel upon its outer end. This screw *n⁴* is tapped into a hole in the bracket *b⁴*, and thereby the entire bracket is adjusted upon the cross-girt *d* transversely of the machine, the bracket *b⁴* having a horizontal extension resting upon the top of the cross-girt underneath the guide *D* and extending across the bed of the machine to give 35 it stability and form a bed for the support of the lumber against the action of the cutters *c¹³ c¹⁴*. This bed part has a slot or hole, *b⁵*, cut through it for the lower cutters to extend up through in working upon the lumber. The bracket *b⁴* has its horizontal part projecting for some distance on the rear side of the cross-girt *d*, and on that side is provided with a down-

ward extension supporting vertical guideways *b³ b³*, similar to those on its upper portion.

The shaft *e* is supported in a box or boxes, *b*, upon a plate, *b⁶*, which moves up and down on the lower guideways, *b³ b³*, of the bracket *b⁴*. A slot is cut through the lower extension of the bracket *b⁴*, and an ear, *b⁷*, (shown in dotted lines in Fig. 6,) is attached to the plate *b⁶* and extends through this slot toward the front end of the machine. A shaft, *s*, is journaled vertically in the bracket *b⁴* and extends downward from above its upper end through the bracket and through the ear *b⁷*. This shaft is 80 screw-threaded at its lower end and fits a corresponding screw-thread in the ear. By turning it the plate *b⁶* is adjusted up and down upon the bracket *b⁴*. An ear, *b⁸*, projecting outward in the same direction from the plate *b²*, between the upper guideways, *b³ b³*, has a shaft, *s'*, journaled in the bracket *b⁴* and extending down through it. This shaft is provided with a screw-thread on its lower end, where it passes through the latter ear, fitted to a corresponding screw-thread in the ear, and the plate *b²* is thus adjusted by turning this shaft *s'* up and down on the upper guideways, *b³*, of the bracket *b⁴*. 90

The shaft *s* has a pinion, *s²*, attached to its upper end, and the shaft *s'* a pinion, *s⁴*. A crank, *s³*, has attached to it a sleeve and pinion, which revolve upon a pin projecting from the upper side of the bracket *b⁴*, and the pinion meshes with the pinions *s³ s⁴*. By turning 100 this crank the upper and lower cutter-heads on the shafts *e e'* are brought nearer together or separated more widely to adjust them to the different lengths of cutters and thickness of material to be tongued. The central guide-strip, *D*, is cut away where the cutters *c¹³ c¹⁴* of the upper cutter-head and the corresponding cutters of the lower cutter-heads pass by it. It will be observed that when the lumber is pressed against the central guide, *D*, by the 110 draft of the feed-rolls acting against the guiding-edges, as shown in Figs. 8 and 10, when passing these cutters, the cutters, especially when the guide strip is made tapering, act principally upon the upper and lower faces of 115 the tongues and merely true the edges of them, and the central guide-strip, *D*, may be used to direct the board to the cutters in this manner, if desired; but I prefer to use it as shown in Fig. 7, where the cutter *c¹³* and its corresponding cutter of the lower head are so placed and the guides so arranged that the lumber is 120 pressed against the side guides, *c² c³*, by slightly angling the side guide, for instance, and the tongue cutters are formed, as shown, so as not only to dress the tongue, but to gage the breadth of the lumber by cutting off its inner edge, so that it may pass snugly between the portion of the central guide, *D*, on the feed-out side of the tonguing-cutters and the opposite side guide, *c² c³*, and so be held firmly 125 against the action of the grooving-cutter head *e* by the central guide opposite to the latter. The tonguing-cutters are thus made to per-

form the dual function of forming the tongue and gaging the breadth of the lumber to accurately pass between the central and side guides, and the portion of the central guide which the lumber meets after passing the tonguing-cutters is made slightly wider than the portion preceding these cutters, to correspond with the amount cut from the edge of the tonguing-cutters, as shown in Fig. 13.

18 Instead of using the cutter-heads upon the horizontal shafts e e' to cut the tongues upon both boards which are being fed through the machine upon each side of the central guide, they may be used with cutters upon only one side of that guide, as shown in Figs. 5, 7, 9, and 10. In the two former the tonguing-cutters are mounted upon the horizontal heads upon the side of the central guide next the side guides, c c' , and in the two latter upon the opposite side. In each case the central guide is made somewhat wider at the feed-out end of the machine, to enable it to act as a guide on both sides to the boards passing out, than previously described, and a central vertical 25 tonguing-head, C , of ordinary construction, is mounted opposite the cutter-heads e e' , to cut the tongue upon the side of the central guide on which the tonguing-cutters on the horizontal heads of shafts e e' are omitted. I thus provide a series of tonguing and grooving cutters 30 adapted to operate upon the opposite sides of two boards independently of each other, and each set of cutters of the series cutting from the planed toward the unplanned portion of the 35 board, and leave a wider space upon the bed of the machine than when separate vertical tonguing and grooving cutter-heads are employed to tongue and groove two boards at once, with their cutters cutting in a similar 40 direction. I prefer, however, to produce the tongues upon both boards, as shown in Figs. 1 and 8, by the horizontal cutter-heads.

When employed with the central vertical cutter-head, C , operating upon the side of the 45 central guide next the side guides, c c' , the central guide-strip, D , has a supplemental guide-strip, D' , added to it on the feed-out side of the cutter-head C , in order to widen it and guide the lumber after it has passed the 50 latter cutter-head. In order to hold the lumber more firmly against the action of the tonguing cutters on the shafts e e' , the central guide, D , is provided with a grooved or recessed edge, 50, where the board comes against it after passing the tonguing-cutters, as shown in Figs. 13 and 14, the recess in the edge of the guide being fitted to receive the tongue formed upon the board M , and thus hold the latter steady and relieve the tongue of injurious pressure in its passage forward under the planing-cylinder and opposite the side cutter-head, c or c' , to receive the groove on its opposite side. In order to further aid in holding the board more firmly when passing 55 the tonguing-cutters, two boards being passed through the machine at the same time, I further employ, in advance of and behind these

described tonguing-cutters of the horizontal shafts e e' , the feed-rolls a a' , one or both divided or made in two separate sections, 20 and 21, one for each board, as shown in Figs. 4, 9; and I regard this as preferable, although a single roll may be employed, as heretofore described. Each board being thus separately held down, there is greater certainty in the 75 presser-roll holding down the edge of the board immediately in advance of the tonguing-cutters than with a single roll. The inner ends of the shafts of the sections 20 and 21 of roll a are mounted in boxes h , fitted in grooves in 80 a hanger, h , depending from the cross-girt 22, the latter being mounted on the upper ends of the feed-roll standards 23 23 and extending across the machine from side to side. Springs are placed above these boxes in this dependent hanger to press them down in the usual manner, and the boxes are raised by screws 24 24, of the ordinary construction. The roll-sections 20 and 21 thus have a yielding pressure upon the boards passing under them, to 90 accommodate them to different thicknesses of lumber. They also act more efficiently than an undivided roller in case the two boards are so passed through the machine simultaneously that one bears against the central guide-strip 95 on one side of it, while the other board on the other side of the central guide takes its bearing against the outer side guide. The difference in frictional resistance to the passage of the boards is in this case added to difference 100 in their thickness.

The central vertical matcher-head, C , is constructed with a spindle attached to the cutter-head, which is seated in an axial hole in the top of the shaft of the head, which carries 105 its driving-pulley in the usual and well-known manner. When the machine is to be used as a single planer, the cutter-head and its spindle are withdrawn from their shaft, and the top of the latter being below the surface of the planer-bed, it presents no obstruction to the planing of lumber as wide as the bed.

When the horizontal shafts e e' are provided with cutters to form tongues on boards on both sides of the guide D , however, and the cutter-head C is not employed, all that is necessary to convert the machine from a duplex to a single planer is to withdraw the shafts e and e' , by means of their screws, upward and downward away from the bed and remove the central guide, D . The cutter-heads c and c' can then be adjusted quite across the bed, toward or away from each other, in the usual manner, which would be impossible with one or more shafts of central vertical cutter-heads like C 120 in the way of and between the former heads. The cutter-head c' , Fig. 4, is thus adjusted in the usual manner by the screw v . Its adjustment, when the center guide, D , is in place in the machine in this manner, enables the operator to gage the width of the board to be matched and dressed on that side of the guide, and obviates the necessity of any readjustment 130 of the guide or the tonguing-cutters on the

shafts $e e'$ on each side of it to accommodate them to different widths of boards to be dressed and tongued and grooved by the machine.

My plan of mounting the tonguing cutters upon the independent shafts $e e'$ instead of upon the planing-cylinders $a a'$, so as to operate upon two boards at once, one on each side of the guide D, not only permits of the machine being transformed into a single planer more readily, as before described, but it also insures a more perfect finish to the tongue, because the shafts are so close together above and below the board as to insure the tongues being cut alike on both sides, which is not always the case when the tonguing-cutters are as far apart on opposite sides of the board longitudinally thereof as the upper and lower planing cylinders, for instance, must be placed, because the warp, unevenness, or twist of the board varies its position slightly with relation to the guides at different parts of the edges of the same, and sufficiently to impair the quality of a tongue cut on its opposite sides at such different points.

25 What I claim as new and of my invention is—

1. The combination, in a wood-planing machine, of feed-rolls, the single long-surface planing-cylinder a , extending across the machine-bed, the guide-strip D, secured centrally and longitudinally upon said bed, and the horizontal shafts $e e'$, extending from one side of said bed transversely across and above and below the same, and each provided at its inner end with two sets of cutters, $c^{13} c^{14}$, adapted to form tongues upon two boards simultaneously upon opposite sides of the said guide-strip D, substantially as described.

2. The combination, in a wood-planing machine, of feed-rolls, the single long planing-cylinder a , extending across the machine-bed, the guide-strip D, secured centrally and longitudinally upon said bed, the horizontal shafts $e e'$, extending from one side of said bed transversely across, above, and below the same, and each provided at its inner end with two sets of cutters, $c^{13} c^{14}$, adapted to form tongues upon two boards simultaneously upon opposite sides of the said guide-strip D, and the cutter-heads $c c'$, adapted to form grooves upon the outer edges of said boards, substantially as described.

3. The combination, in a wood-planing machine, of two independent pressure-rolls, 20 21, extending, respectively, part way across the lumber-supporting surface, the single long planing-cylinder a , extending across the machine-bed, the guide-strip D, secured centrally and longitudinally upon said bed, the horizontal shafts $e e'$, extending from one side of said bed transversely across, above, and below the same, and each provided at its inner end with two sets of cutters, $c^{13} c^{14}$, adapted to form tongues upon two boards simultaneously upon opposite sides of the said guide-strip D, and the cutter-heads $c c'$, adapted to form grooves upon the outer edges of said boards, substantially as described.

4. The combination, in a wood-planing machine, of feed-rolls, the single long-surface planing-cylinder a , extending across the machine-bed, the guide-strip D, secured centrally and longitudinally upon said bed, the horizontal shafts $e e'$, extending from one side of said bed transversely across, above, and below the same, and each provided near its inner end 70 with two sets of cutters, $c^{13} c^{14}$, adapted to form tongues upon two boards simultaneously upon opposite sides of said guide-strip D, and the cutter-heads $c c'$, provided with adjusting mechanism adapted to adjust their position 80 nearer to or farther from said guide-strip D transversely of the machine-bed, substantially as described.

5. The combination, in a wood-planing machine, of the feed-rolls, the single long-surface 35 planing-cylinder a , extending across the machine-bed, the guide-strip D, secured centrally and longitudinally upon said bed, the horizontal shafts $e e'$, extending from one side of said bed transversely across, above, and below 90 the same, and each provided near its inner end with a set of cutters, c^{13} , adapted to form a tongue upon the inner edge of a board upon one side of guide-strip D, and the side cutter-head, c , and side guide c^2 , each provided with 95 adjusting mechanism adapted to adjust its position nearer to or farther away from said guide-strip D transversely of the machine-bed, substantially as described.

6. The combination, in a wood-planing machine, of the feed-rolls, the single long-surface planing-cylinder a , extending across the bed 100 of the machine, the guide-strip D, secured centrally and longitudinally upon said bed, and formed with guiding-edges for the lumber expanding outward from its center line toward the feed-out end of the machine, the horizontal shafts $e e'$, extending from one side of said bed transversely across, above, and below the same, and each provided with two sets of cutters, $c^{13} c^{14}$, adapted to form tongues upon two boards simultaneously upon opposite sides of said guide-strip D, substantially as described.

7. The combination, in a wood-planing machine, of the feed-rolls, the single long-surface 115 planing-cylinder a , extending across the machine-bed, the guide-strip D, secured centrally and longitudinally upon said bed, the horizontal shafts $e e'$, extending from one side of said bed transversely across, above, and below 120 the same, and each provided near its inner end with a set of cutters, c^{13} , adapted to form a tongue upon the inner edge of a board upon one side of the guide-strip D, and the side cutter-head, c , and side guides, $c^2 c^3$, each provided with 125 adjusting mechanism adapted to adjust its position nearer to or farther away from said guide-strip D transversely of the machine, substantially as described.

8. The combination, in a wood-planing machine, of the feed-rolls, the single long-surface 130 planing-cylinder a , extending across the machine-bed, the guide-strip D, secured centrally and longitudinally upon said bed, the hori-

5 horizontal shafts $e' e'$, extending from one side of said bed transversely across, above, and below the same, and each provided near its inner end with a set of cutters, c^3 , formed and adapted to reduce the board to a predetermined width by removing its edge and cut a tongue upon the finished inner edge of the same, in conjunction with the side guides, c^2 and c^3 , and cutter-head c , adapted to form a groove upon its opposite edge, substantially as described.

9. The combination, in a wood-planing machine, of the feed-rolls, the single long-surface planing-cylinder a , extending across the machine-bed, the guide-strip D , secured centrally and longitudinally upon said bed, the horizontal shafts $e' e'$, extending from one side of said bed transversely across, above, and below the same, and each provided near its inner end with a set of cutters adapted to form a tongue upon the inner edge of a board pressing against said guide-strip D in its passage through the machine, the side cutter-head, c , adapted to form a groove upon the opposite side of said board, and the central cutter-head, C , supplemental central guide-strip, D' , side cutter-head, c , and side guides, $c^2 c^3$, adapted to guide another board through said machine on the opposite side of the guide-strip D and form the tongue and groove upon the edges of the same simultaneously with the first one, substantially as described.

10. The combination, in a wood-planing machine, of the side guides, c^2 and c^3 , and side cutter-head, c , moving on guideways transversely of the machine-bed, and provided with independent adjusting-screws for adjusting the same thereon, the longitudinal shaft c^4 , coupled together in sections or divisions, one of which sections or divisions is geared to the adjusting-screws of each of said guides and cutter-head, respectively, and independent crank or hand-wheel mechanism applied to each of said sections or divisions of said shaft c^4 , whereby the sections of the same may be coupled together and adjust said guides and cutter-head simultaneously, or one or more sections may be uncoupled and operated to adjust its guide or cutter-head independently of the others, substantially as described.

11. The combination, in a wood-planing machine, of the side guide c^3 , the side cutter-head, c , and the side guide c^2 , made adjustable transversely of the machine upon guide-ways, and provided with screws operating to adjust them independently, respectively, and the shaft c^4 , divided into sections, each section being separately geared to the adjusting-screws of one of said guides and said cutter-head, respectively, and the sleeve-couplings $c^8 c^{10}$, uniting said sections of said shaft and forming bearings wherein one section may revolve upon and be supported by the other, substantially as described.

12. The combination, in a wood-planing machine, of the feed-rolls, the single long-surface planing-cylinder a , extending across the ma-

chine-bed, the horizontal shafts $e' e'$, extending from only one side of said bed transversely across, above, and below the same, each provided at its inner projecting end with a set of cutters, c^3 , formed and adapted to reduce the board to a predetermined width and cut a tongue upon the inner edge of the same, in conjunction with the adjustable side guides, $c^2 c^3$, and side cutter-head, c , made adjustable transversely of the machine-bed, and the latter adapted to form a groove upon the outer edge of the board, substantially as described.

13. The combination, in a wood-planing machine, of the feed-rolls, the single long-surface planing-cylinder a , extending across the bed of the machine, the guide-strip D , secured centrally and longitudinally upon said bed, the horizontal shafts $e' e'$, extending from one side of said bed transversely across, above, and below the same, each provided near its inner end with a set of cutters, c^3 , formed and adapted to reduce the board to a predetermined width by removing its edge and cut a tongue upon the finished inner edge of the same, in conjunction with the side guides, $c^2 c^3$, and cutter-head c , made adjustable transversely of the machine-bed, and the latter adapted to form a groove upon the outer edge of the board, substantially as described.

14. The combination, in a planing-machine, of the feed-rolls, the single long-surface planing-cylinder a , extending across the bed of the machine, the tapering guide-strip D , secured centrally and longitudinally upon said bed, the horizontal shafts $e' e'$, extending from one side of said bed transversely across, above, and below the same, each provided near its inner end with two sets of cutters, $c^3 c^4$, adapted to form tongues upon the inner edges of two boards passing simultaneously through the machine and guided against the opposite edges of said guide-strip, substantially as described.

15. The combination, in a wood-planing machine, of the single long planing-cylinder a , extending across the bed of the machine, the guide-strip D , secured centrally and longitudinally upon said bed, the horizontal shafts $e' e'$, placed in advance of said planing-cylinder, and each provided with two sets of cutters, $c^3 c^4$, adapted to form tongues upon the inner edges of two boards passing simultaneously through the machine on opposite sides of said guide-strip, and the feed-roll a^2 , placed in advance of said shafts $e' e'$, and adapted to press the boards down upon the bed in advance of the same, substantially as described.

16. The combination, in a wood-planing machine, of the single long planing-cylinder a , extending across the bed of the machine, the guide-strip D , secured centrally and longitudinally upon said bed, the horizontal shafts $e' e'$, placed in advance of said planing-cylinder, each provided with two sets of cutters, $c^3 c^4$, adapted to form tongues upon the inner edges of two boards passing simultaneously through the machine on opposite sides of said guide-strip, the feed-roll a^2 , placed in advance

of said shafts e e' and divided into two sections, 20 21, adapted to independently press said boards down upon the bed in advance of the same, substantially as described.

5 17. The combination, in a wood-planing machine, of the single long planing-cylinder a , extending across the bed of the machine, the guide-strip D, secured centrally and longitudinally upon said bed, the horizontal shafts e e' , placed in advance of said planing-cylinder, each provided with two sets of cutters, c^{13} c^{14} , adapted to form tongties upon the inner edges of two boards passing simultaneously through the machine on opposite sides of said guide-strip, the feed-roll a^2 , placed in advance of said shafts e e' , and the feed-roll a^3 , placed behind said shafts and in advance of said cylinder a , each of said rolls being divided into two sections adapted to independently press said 20 boards down upon the bed, substantially as described.

18. The combination, in a planing-machine, of the single long planing-cylinder a , extending across the bed of the machine, the guide-strip D, secured centrally and longitudinally upon said bed, the horizontal shafts e e' , placed in advance of said planing-cylinder, each provided with two sets of cutters, c^{13} c^{14} , adapted to form tongties upon the inner edges of two 25 boards passing simultaneously through the machine on opposite sides of said guide-strip, the feed-rolls a^2 a^3 , placed in advance of and behind said shafts, and the side cutter-heads, c c' , adapted to groove the outer edges of said 30 boards, substantially as described.

19. The combination, in a planing-machine, of the single long planing-cylinders a a' , extending across the bed of the machine, the guide-strip D, secured centrally and longitudinally upon said bed, the horizontal shafts e e' , placed in advance of said planing-cylinders, each provided with two sets of cutters, 40 c^{13} c^{14} , adapted to form tongties upon the inner

edges of two boards passing simultaneously through the machine on opposite sides of said 45 guide-strip, the adjustable side guides, c^2 c^3 , the feed-rolls a^2 a^3 a^4 , placed in advance of and between said shafts and cylinder a and behind cylinder a' , and the side cutter-heads, c c' , substantially as described.

50 20. The combination, in a wood-planing machine, of the single long planing-cylinder a , extending across the bed of the machine, the guide-strip D, secured centrally and longitudinally upon said bed, the horizontal shafts e e' , placed in advance of said cylinder, each provided with two sets of cutters, c^{13} c^{14} , adapted to form tongties upon the inner edges of two boards passing simultaneously through the machine on opposite sides of said guide-strip, 60 the adjustable side guides, c^2 c^3 , the feed-rolls a^2 a^3 , each divided into sections 20 21, adapted to independently press upon and carry forward said boards, one bearing against said central guide-strip upon one side thereof and the 65 other against said side guides, c^2 c^3 , upon the other side of the central guide-strip, and the side cutter-heads, c c' , adapted to groove the outer edges of said boards, substantially as described.

70 21. The combination, in a wood-planing machine, of the feed-rolls, the single long planing-cylinder a , extending across the bed of the machine, the guide-strip D, secured upon said bed and provided in those portions of its edge 75 or edges against which the board bears after being tongued with recesses adapted to receive the tongue and take the pressure off of the edge of the same, and the side cutter-heads, c c' , adapted to form grooves in the 80 outer edges of said boards, substantially as described.
